UNITED STATES PATENT OFFICE.

EDGAR G. CASAD, OF OAKLAND, CALIFORNIA.

METAL SEPARATOR.

Application filed February 13, 1922. Serial No. 535,973.

To all whom it may concern:

Be it known that I, EDGAR G. CASAD, a citizen of the United States, residing at Oakland, in the county of Alameda and State of California, have invented certain new and useful Improvements in Metal Separators, of which the following is a specification.

My invention is an improved ore separator by means of which heavy ores, such as flower gold and platinum may be separated mechanically from the dirt without the use of mercury or other chemicals.

Referring to the drawings forming a part of this specification:

Figure 1 is a side elevation of my ore separator.

Figure 2 is a plan view of my separator.

Figure 3 is a transverse vertical section of my separator on the line 3—3 of Figure 1 looking toward the right.

Figure 4 is a plan view of the upper separator tray.

Figure 5 is a fragmentary plan view of the lower separator tray.

Figure 6 is a sectional view of the lower tray.

In the drawings 1 indicates a frame comprising four standards 2—2 and 3—3, upper rails 4 secured to the upper ends of said standards, lower rails 5 secured to the lower part of said standards, uprights 6 connected to rails 4 and 5 midway between the standards 2 and 3, transverse rail 7 connecting the upper rails 4—4 and transverse rails 8 connecting the rails 5—5. The rails 4 and 5 incline downwardly at a slight angle from the standards 3 to the standards 2. A hopper 9 is mounted on the high end of the rails 4—4 in which hopper is an inclined bottom 10 which inclines downwardly towards the said end of the frame, said bottom being provided with a transverse row of holes 11 near its lower edge.

Suspended on flexible straps 12 secured to the upper rails 4—4 is a trough 13 which inclines downwardly from under the hopper to the opposite end of the separator parallel to said upper rail. In the bottom of said trough is a tray 14, the bottom of which tray is formed with riffles 15 extending transversely of the tray. Above the tray 14 in the upper part of the trough 13 is mounted a tray 16 which is provided with perforations 17 in its high end under the hopper 9 and a short distance below said hopper.

On the rail 8 at the high end of the frame 1 is mounted a motor 18 the shaft 19 of which extends longitudinally of the machine parallel to rails 5 and is journaled in a bearing 20 on the rail 8 at the lower end of the machine. A shaft 21 is journaled parallel to the shaft 19 in bearings 22, 23 and 24 on one of the standards 2, one of the uprights 6 and one of the standards 3. On the shafts 19 and 21 are pulleys 25 and 26 respectively over which travel a belt 27. On the shaft 21 near its respective ends are secured eccentrics 28 and 29 which turn within scotch yokes 30 and 31 secured to the under side of the trough 13.

A pump 35 is mounted on one of the cross rails 8 through which pump extends the shaft 19 on which is secured the pump piston. An inlet pipe 36 connects to the pump which pipe is placed in a stream or other source of water supply. A pipe 37 leads from the outlet of said pump into the hopper 9 just above the high end of the bottom 10.

The tray 14 consists of two side walls 40—40, an upper end wall 41, a bottom wall 42 extending from the end wall 41 a short distance and the riffles 15 which extend from the lower edge of said bottom wall 42 to the lower end of the tray. The riffles comprise a plurality of metal trough-shaped riffle sections, each of which is bent downwardly upon itself at one edge forming flanges 43 which fit over the other edge of the adjacent section, said sections resting in the bottom of the tray 14 and secured at their ends to the side walls 40—40. The tray 14 is shorter than the trough, its upper end wall 41 resting just above the first row of holes 17. A plate 44 is mounted in the upper end of the trough under the perforations 17 and above the tray 14 and extends downwardly over the upper end wall 41 of the tray 14.

Ore dirt is placed in the hopper 9 and water is pumped therein, by the pump 35 through pipe 37. The water washes the ore down the bottom 10 through the holes 11 into the high end of the tray 16 from which the rocks and so forth pass down and out the lower end of said tray and the ore dirt passes through holes 17 onto plate 44 and into the upper end of the tray 14 and over the riffles 15, where the ore settles in the riffles 15 and the sand passes out of the lower end of the tray. While the ore dirt passes through the machine the trough 13, plate 44, and the trays 110

14 and 16 are agitated by the motor 18 through the medium of the shaft 19, pulley 25, belt 27, pulley 26, shaft 21, eccentrics 28 and 29 and scotch yokes 30 and 31. The ore is readily recovered from the tray 14.

Having described my invention, I claim:

1. In an ore separator, a frame, an inclined trough mounted on said frame, a tray in the bottom of said trough and extending longitudinally thereof, the bottom of said tray being corrugated, means whereby one side of said trough is reciprocated and the other side thereof is gyrated, said reciprocation being substantially transversely of said trough.
2. In an ore separator as described, a frame, an inclined trough mounted on said frame, a tray in the bottom of said trough, the bottom of said tray being corrugated, a tray in the upper part of said trough provided with perforations in its high end, and means for gyrating one side of said trough while reciprocating the other side thereof.
3. In an ore separator as described, a frame, an inclined trough mounted on said frame, a tray in the bottom of said trough, the bottom of said tray being corrugated, and a tray in the upper part of said trough provided with perforations in its high end, a hopper above the high end of said trough, the bottom wall of said hopper inclining downwardly toward the high end of said trough, the lower end of said bottom wall being perforated.
4. In an ore separator as described, a frame, flexible straps secured to said frame, an inclined trough suspended on said straps,

a tray in the bottom of said trough, the bottom of said tray being corrugated, a tray in the upper part of said trough provided with perforations in its high end, a shaft journaled on said frame, eccentrics on said shaft, and scotch yokes rigidly secured to said trough and adapted to be operated by said eccentrics.

5. In an ore separator as described, a frame, an inclined trough flexibly mounted on said frame, a hopper above the high end of said trough, a drive shaft journaled on said frame, a motor for driving said shaft, means operated by said shaft for gyrating one side of said trough while reciprocating the other side thereof.

6. In an ore separator, a frame, an inclined trough mounted on said frame, a plate in the upper end of said trough, a tray with riffles in the bottom of said trough extending from the lower end of the trough to a point just under the lower edge of said plate, and a tray in the trough above said plate and said tray, said latter tray having perforations in its upper end over said plate and means for gyrating one side of said trough while reciprocating the other side thereof.

7. In an ore concentrator, a frame, a trough, flexible means connecting the frame and the trough, a shaft, eccentrics on the shaft and means connecting the eccentrics and the trough whereby one side of the trough is reciprocated in the arc of a circle and the other side is gyrated.

In testimony whereof I affix my signature.

EDGAR G. CASAD.
